Primary Examiner—M. N. Pandozzi*(74) Attorney, Agent, or Firm*—Stephen E. Feldman, P.C.(57) **CLAIM**

The ornamental design for a border for a plate or bowl, as shown and described.

DESCRIPTION

FIG. 1 is a top plan view of a border for a plate or bowl showing my new design;

FIG. 2 is a side elevation view thereof;

FIG. 3 is a bottom plan view thereof;

FIG. 4 is a side elevation view thereof;

FIG. 5 is a top plan view of a border for a plate or bowl showing a second embodiment of my new design;

FIG. 6 is a side elevation view thereof;

FIG. 7 is a bottom plan view thereof; and,

FIG. 8 is a side elevation view thereof.

The broken lines in the drawings are for illustrative purposes only and form no part of the claimed designs.
